UNITED STATES PATENT OFFICE.

CHARLES M. DE LACY, OF BROOKLYN, ASSIGNOR OF TWO-THIRDS TO
ROBERT SEAMAN, OF NEW YORK, N. Y.

CAP.

SPECIFICATION forming part of Letters Patent No. 430,003, dated June 10, 1890.

Application filed January 2, 1890. Serial No. 335,628. (No model.)

To all whom it may concern:

Be it known that I, CHARLES M. DE LACY, a citizen of the United States, residing at South Brooklyn, in the county of Kings and 5 State of New York, have invented certain new and useful Improvements in Caps, of which the following is a description.

My invention relates to certain improvements in caps, particularly of the class commonly called "traveling-caps," which are usually made of silk or very light cloth. My invention is also intended to be applied to caps for persons engaged in indoor and outdoor athletic sports, in which a light cool covering for the head is very desirable. As heretofore made caps for these purposes have been objectionable in that they were too warm and heavy, and I therefore seek to obviate these objections and produce a cap which may 15 be made of any suitable material and shape and yet be light, cool, and a sufficient covering and protection to the head.

To this end my invention consists in a cap comprising a band or brim of silk or other 20 suitable material and a top or crown of reticulated fabric—such as silk, cotton, or the like—the two being connected by a rim, as I will proceed now particularly to set forth, and finally claim.

30 In the accompanying drawings, in which like parts are designated by similar letters of reference, Figure 1 is a perspective view of a cap embodying my invention, and Fig. 2 an enlarged section thereof.

a designates the band or brim, and *b* the 35 top or crown. As shown, the brim is provided with a lining *c*, and has attached to it a circular rim *d*, to which the crown *b* is secured. The crown is preferably made of silk or cotton woven or knitted, so as to form an open 40 mesh throughout, and the crown is then attached to the rim by stitching or in any suitable manner. In some cases it will be preferable to omit the lining and make the rim as an extension of the brim.

45 A cap of this construction will be light and comfortable and at the same time will afford all the protection necessary to the head for travelers and persons indoors and persons engaged in athletic sports.

50 What I claim as my invention, and desire to secure by Letters Patent, is—

As an improved article of manufacture, a cap comprising a band *a* of closely-woven material, a rim *d*, arranged in the upper part of 55 such band, and a crown *b* of reticulated material attached to said rim, substantially as described.

56 In testimony whereof I have hereunto set my hand this 31st day of December, A. D. 1889.

CHAS. M. DE LACY.

In presence of—

THORNE S. WALLING,
FREDERIC CARRAGAN.
